SHUTTLE CHECKING MECHANISM

Albert A. Gorden, Worcester, Mass., assignor to Crompton & Knowles Loom Works, Worcester, Mass., a Corporation of Massachusetts

Application December 30, 1931
Serial No. 583,931

5 Claims. (Cl. 139—187)

This invention relates to fly shuttle looms and to means for checking a shuttle therein. Trouble has been encountered in the operation of wide looms at high speed, on account of the difficulty in effectively stopping a rapidly moving and relatively heavy shuttle without rapid destruction of the picker. Furthermore, the application of heavy binder pressure increases the power consumed in picking and causes frequent breakage of picker sticks. Also in automatic looms it is found difficult to stop a high speed shuttle in the predetermined position in the shuttle box which is required for successful transfer.

It is the object of my invention to provide an improved shuttle checking mechanism by which a high speed shuttle may be easily and accurately boxed in a predetermined position, the binder pressure on said shuttle being largely released before the shuttle is again picked.

A further object of my invention is to provide a single operating means by which the checking mechanism at both sides of the loom may be actuated from a single cam.

My invention further relates to arrangements and combinations of parts which will be herein-after described and more particularly pointed out in the appended claims.

A preferred form of the invention is shown in the drawings, in which

Fig. 1 is a side elevation of portions of a loom, partly in section, and showing my invention applied thereto;

Fig. 2 is an enlarged front elevation of the drop boxes at one end of the lay, looking in the direction of the arrow 2 in Fig. 1;

Fig. 3 is a detail sectional plan view, taken along the line 3—3 in Fig. 5;

Fig. 4 is a still further enlarged front elevation of the drop boxes;

Fig. 5 is a partial plan view, looking in the direction of the arrow 5 in Fig. 4, and

Fig. 6 is a diagrammatic view of certain actuating connections to be described.

Referring to the drawings, I have shown portions of a loom including a loom side 10 and a lay 11 supported on swords 12 swinging about the usual rock shaft 13 and oscillated by the usual connecting rods 14. The lay 11 is provided with a lay end 15 having guide-ways 16 and 17 for a set of vertically shiftable drop boxes 20. The drop boxes 20 are mounted at the upper end of a lifter rod 21, actuated by the usual box-lifting mechanism, not shown.

Each drop box 20 is provided with a binder 25

pivoted at 26 to a binder-supporting member 27. These several supporting members 27 are pivoted on a single stud 28, mounted in bearings in the frame of the drop boxes 20.

A binder spring 30 is mounted on each supporting member 27 and extends rearward through an opening 32 therein to engage the front face of the associated binder 25.

Each binder 25 is extended toward the outer end of the lay beyond its pivot 26, as indicated at 35, and this extended portion is preferably shaped to substantially conform to the tapered end of the shuttle S engaged thereby.

Each supporting member 27 is also extended beyond its pivot 28, as indicated at 37, and is provided with a stop screw 38 threaded in said member and secured in adjusted position by a lock nut 39. The stop screws 38 engage the front face of an end portion of the drop boxes 20 and limit forward swinging movement of the supporting members 27 under the influence of the springs 30.

A rock shaft 40 is mounted in a bearing 41 (Fig. 4) beneath the lay end 15 and in a depending bearing bracket 42 (Fig. 6) at the opposite end of the lay 11. Presser arms 44 and 45 are mounted on the rock shaft 40 and extend upward to engage the binder supporting members 27 associated with the active shuttle.

In Fig. 6 I have shown the invention applied to a 4 x 1 loom, in which case the presser arm 45 engages a single supporting member 27 at the plain end of the loom, while the presser arm 44 engages any one of four supporting members 27 at the drop box end, as shown in Fig. 4. It will be obvious that the invention may be used without change on a plain or 1 x 1 loom, or on a pick-and-pick loom having a plurality of shuttle boxes at each end of the lay. Also obviously it can be applied at one end only of either a plain or a drop box loom.

The rock shaft 40 is provided with a rearwardly extending arm 50 (Figs. 1 and 2) which is connected by a link 51 to the front end of a rocking cam lever 52 mounted on a fixed pivot 53 and provided with a cam roll 54 engaging a double cam 55 on the usual bottom or cam shaft 56 of the loom. This shaft ordinarily makes one revolution for each two picks of the lay and is accordingly provided with two raised portions 57 and with two depressed portions 58, all symmetrically arranged and each portion being preferably concentric with the axis of the cam shaft 56.

An additional arm 60 (Fig. 2) extends rear-

ward from the rock shaft 40 and is connected by a link 61 to a light spring 62 by which the offset upper ends 64 of the presser arms 44 and 45 are held yieldingly against the ends of selected 5 supporting members 27.

The usual protector fingers 70 are mounted on a protector rod 71 (Fig. 6) and engage the extreme end portions of the binders 25 associated with the active shuttle. The protector fingers 10 operate in the usual way and their operation is not modified by any change in the construction and mounting of the binders. Stop rods 73 and 74 (Fig. 6) limit the outward movement of the binders when engaged and abruptly displaced 15 outwardly by the boxing of a shuttle.

Having described the details of construction of my improved shuttle-checking mechanism, the method of operation and advantages thereof will be readily apparent. The upper end 64 of 20 each presser arm 44 or 45 engages the outer end portion of a supporting member 27 which is associated with the active shuttle box.

Assuming that the shuttle is about to enter 25 the shuttle box, the cam roll 54 will be engaged by one of the raised portions 57 of the cam 55, thus applying a positive pressure to the active supporting member 27. This causes rearward movement of the pivot 26 and also increases the pressure of the associated binder spring 30. The 30 shuttle thus enters the shuttle box against this relatively heavy resistance of the binders 25.

As the shuttle closely approaches final boxed 35 position, the tapered end of the shuttle engages the extended portion 35 of the binder, with a tendency to swing this portion 35 outward and thus increase the pressure of the straight portion of the binder against the side of the shuttle.

The shuttle is thus brought to rest in a pre-determined position and is firmly held against 40 rebound.

As soon as the shuttle is boxed, the cam roll 45 54 enters a depressed portion 57 of the cam 55, which relieves the positive pressure on the supporting member 27. The member 27 is therefore 50 upon swung around its pivot 28 by the reaction of the binder spring 30 until the stop screw 38 engages the surface of the drop boxes 20. Such movement of the member 27 substantially reduces the binder pressure on the shuttle S, first 55 by moving the binder pivot 26 forward, and second by reducing the pressure of the binder spring 30.

The boxes may then be shifted vertically, as 60 very light pressure is being applied through the presser arm 44, and the shuttle may be picked against the reduced and relatively light binder resistance. This substantially reduces the power

required for picking and also reduces the breakage of picker sticks.

As soon as the shuttle has been picked, pressure is again applied through the presser arms 44 and the parts are again placed in readiness 80 to receive and effectively box the shuttle.

As previously stated, the invention may be applied to either one or both ends of a loom and may be used with a single shuttle box or with a plurality of drop boxes as desired. The 85 invention is simple in construction and reliable in operation and is very effective for the intended purposes.

It is to be particularly noted that the movement of the supporting member 27 not only 90 varies the position of the binder pivot but also varies the pressure of the binder spring.

The stop screws 38 limit the swinging movements of the supporting members 27 when released, and thus determine the minimum binder 95 spring pressure when the shuttle is picked.

Having thus described my invention and the advantages thereof, I do not wish to be limited to the details herein disclosed, otherwise than as set forth in the claims, but what I claim is.— 100

1. In a loom, a shuttle box, a binder, a pivoted supporting member on which said binder is movably mounted, a binder spring mounted on said supporting member and engaging said binder, and additional positive means to move 105 said supporting member toward said shuttle just prior to the boxing of the shuttle, thereby increasing the binder spring pressure.

2. In a loom, a shuttle box, a binder, a pivoted supporting member on which said binder is movably mounted, a binder spring mounted on said supporting member and engaging said binder, and means to move said supporting member toward the shuttle just prior to the boxing of the shuttle and to simultaneously increase the binder 115 spring pressure.

3. In a loom, a shuttle box, a binder, a binder spring, means to move said binder toward the shuttle box just prior to the boxing of the shuttle, and means to simultaneously increase the 120 spring pressure on said binder.

4. In a loom, a shuttle box, a binder, a binder spring, means to move said binder toward the shuttle box just prior to the boxing of the shuttle, thereby simultaneously increasing the spring 125 pressure on said binder, said means being thereafter effective to relieve the binder pressure before the shuttle is picked.

5. The combination in a loom as set forth in 130 claim 4, in which means is provided for selectively establishing the minimum binder pressure.

ALBERT A. GORDON.
